UNITED STATES PATENT OFFICE.

JOSEPH LEISCH, OF TRYON, NORTH CAROLINA, ASSIGNOR TO THE JOHN CHURCH COMPANY, OF CINCINNATI, OHIO, A CORPORATION OF OHIO.

PLAYER-PIANO.

1,212,369.

Specification of Letters Patent. Patented Jan. 16, 1917.

Application filed April 21, 1913. Serial No. 762,606.

To all whom it may concern:

Be it known that I, JOSEPH LEISCH, a citizen of the United States, and a resident of Tryon, in the county of Polk and State of 5 North Carolina, have invented certain new and useful Improvements in Player-Pianos, of which the following is a full, clear, and exact description, reference being made to the accompanying drawings, forming part 10 of this specification.

My invention has relation to player pianos in which the piano keys are operated by pneumatic action, controlled by means of a tracker board over which is fed a perforated 15 sheet, whose perforations are adapted to admit atmospheric pressure in selected tracker tubes carried by the said board.

The object of my invention is to provide a construction for such pianos whereby selected notes may be accented, thus carrying 20 a melody along with an unaccented accompaniment, and whereby the relative strength of tone between melody and accompaniment may be varied further at the will of the 25 performer, and whereby general fortissimo and pianissimo effect may be gained without disturbing the relations.

The invention consists of that novel construction and arrangement of perforated 30 music roll, tracker tubes, pneumatics and valves, to be hereinafter specifically pointed out and claimed.

In the drawings, Figure 1 is a vertical section of one of the loud and soft boxes. 35 Fig. 2 is a vertical section of one power pneumatic with its direct controlling and auxiliary controlling pneumatics and valve. Fig. 3 is a rear elevation, partly in section, of a portion of the pneumatic chest, showing 40 the base and treble divisions of the loud and soft control. Fig. 4 is a plan view illustrating the music roll and tracker tube opening. Fig. 5 is a side elevation of a single 45 tracker tube showing the new branching feature.

I have shown in the drawings no view of an entire pneumatic chest with its connections, conceiving this to be unnecessary in view of the fact that it is not desired to 50 claim any especial arrangement of power pneumatics, and also that the arrangement of a pneumatic chest to accommodate the devices to be described would present no difficulty to one skilled in the art. I have

shown in Fig. 3 the manner of dividing the 55 chest into base and treble parts by means of the wall A.

The tracker tube 1 is divided into the 60 branches 2 and 3, of which branch 2 admits atmospheric pressure to the direct pneumatic system. As illustrating any desired system for direct operation of power pneumatics, I provide the vacuum chamber 4, with the bleed 5 opening into the tube 2. The pouch 6 is located over the opening of the 65 tube 2 into the vacuum chamber, and carries the primary valve having the disks 8 and 9 and the stem 10. The raising and lowering of the primary valve by means of the pouch alternately opens to atmospheric 70 or vacuum connection the secondary tube 11. The secondary tube opens into a secondary 75 vacuum chamber 12 over which opening is placed the pouch 13 which carries the secondary valve. The secondary valve has a 80 stem 14 and the disk 15 which opens and closes the passageway 16 leading from the power pneumatic, to the vacuum chamber 12. The valve stem 14 finds a guide in any usual manner in the opening 17 from the passageway 16 to the atmosphere. The power pneumatic into which the said passageway leads 85 is constructed in any ordinary manner with a fixed member 18, folds 19 and a movable member 20. The movable member carries 90 the extension 21, adapted to contact with the lug 22 of the sticker 23 of the piano action. The movable member of the bellows carries 95 within a contact cushion 24. This cushion contacts with the movable member 25 of a small bellows (or pneumatic if desired) 26, which bellows is adapted to serve as a stop for the movable member 20 of the power pneumatic, and which constitutes the essential 100 feature of the construction within the power pneumatic. Leading into the bellows 26, whose fixed member is that of the power pneumatic, is an opening 27. From this opening the tube 28 leads to the chambers, valves and pneumatic to which atmospheric 105 pressure is admitted by the branch 3 of the tracker tube 1.

The branch 3, into which leads the bleed 29, opens into a vacuum chamber 30. Over the opening is located a pouch 31 of material considerably less elastic and light in weight than the pouch 6 in the direct controlling system for a purpose to be herein-

after explained. This pouch carries a valve having a stem 32 and disk 33. The disk is located in a chamber 34 which leads into the tube 28 of the interior bellows, and is 5 adapted to open this chamber to the vacuum chamber 30 and close it from an upper chamber 35 which is connected with the loud and soft box and is normally open to the said chamber. If owing to the toughness of 10 the pouches 6 and 31, the former is raised so quickly upon full exposure of a tracker slot that it gets ahead of the latter; this getting out of time may be counteracted by a regulation of the toughness of the pouch 15 31. Comparative toughness is, moreover, merely my preferred form for regulating sensitiveness of pouches or pneumatics, and I do not wish to be limited to it alone, as other means might readily be contrived. 20 Thus it can be seen that if the tough pouch 31 is raised by a strong admission of air at atmospheric pressure, the interior bellows of the power pneumatic will be deflated into the vacuum chamber 30, allowing the un- 25 hampered action of the said power pneumatic; and it can further be seen that no matter what condition of pressure may prevail in the chamber 35, it will be cut off from communication with the interior bellows 30 when the pouch 31 is raised.

It will be apparent by reference to Fig. 3, that the chambers 35 and 30 are common to the entire base or treble system, and that the chambers 34 are separate for each 35 pneumatic.

Turning then to the manner of admitting air at atmospheric pressure to the two systems shown in Fig. 2, the tracker board of the usual formation, with the desired number of ducts 136 (Figs. 4 and 5),—from these ducts the tubes 1 lead to their respective pouches as already described by the branches 2 and 3. The music roll 137 of perforated paper is provided mainly with 40 slits or perforations 138, of a width considerably less than the width of the ducts 136 with which they are to register. In making up the roll, all notes desired to be brought out above accompaniment, melodies 45 and thematic notes, are cut in the music roll in wide slits 139 equal to the width of the ducts. By this means reduced atmospheric pressure is admitted to the tubes wherein it is not desired to have maximum stroke, 50 which pressure will force up the pouch operating the primary valve in the direct system, and will not be able to force up the pouch operating the valve in the interior bellows system. When it is desired to have 55 maximum power, then a wide slot is provided which allows full atmospheric pressure in the tube, and overcomes the greater resistance to suction of the tough pouch in this secondary system. It has been stated 60 that the operation of this pneumatic pouch

31 throws the tube 28 to the inferior bellows, out of connection with the chamber 35, which said chamber is connected with the loud and soft box. The connection so mentioned is by means of the tube 36. There is 70 a loud and soft box for the treble and one for the base, and one connection is necessary for each one in the said chamber, 35 being common to all the "supplementary pneumatic" series of treble and base respectively. 75 By controlling the pressure within the chamber 35, it can be seen that all of the interior bellows not thrown out of connection with the chamber 35, are thereby controlled in common. It is the purpose of the 80 loud and soft box to give this control, or in other words to permit the changing of the strength of tone of the accompaniment portion of a series of notes without affecting the melody or solo portion. This apparatus 85 consists in a common chamber or channel 37, provided with connections 36 aforementioned, and with ports 38 to atmosphere, 39 to air at pressure greater than atmosphere, and 40 to a vacuum or pressure below 90 atmosphere.

A chamber 41 is provided, adapted to contain the air at pressure greater than atmosphere, and a bellows 42 located therein adapted to carry the valve 43. This valve 95 has disks 44 and 45 connected by the stem 46, which when seated close the ports 38 and 39 above mentioned respectively thus admitting atmospheric or pressure greater than atmosphere to the common chamber 37. 100 Leading into the bellows 42 is the passageway 47 which has openings 48 and 49 to the atmosphere and to the pressure chamber respectively. Between these openings reciprocates the valve disk 50, carried by the stem 105 51. The stem is attached to a pouch 52 which is located over the opening of a tube 53. The tube 53 is kept normally under compression through the bleed 54, and the operating connection 66 (Fig. 1) leads from the tube 54 110 to the keyboard of the piano (not shown). When the tube 53 is opened to the air, however, the pressure in the chamber 41 deflates the pouch 52, closing thus the port 49 to the bellows passageway, and said port being 115 closed deflates the bellows 42 through the port 48. By doing this the valve 43 is allowed to fall admitting compressed air to the chamber 37. This compression is admitted into the tube 28 by the various connections described and makes a greater resistance in the interior bellows of the power pneumatic, thereby stopping the stroke of the movable member of the said power pneumatic. The opening of this series to a 125 vacuum in a like manner removes resistance from the stroke of said movable member. To accomplish this, vacuum chamber 56 is provided, into which opens a tube 57 having a bleed 58. Over the opening is located a 130

pouch 59 carrying a primary valve with disks 60 and 61, which open or close to air or vacuum the secondary tube 62. This secondary tube opens into vacuum chamber 63, said opening being covered by the pouch 64. This pouch carries a valve whose disk 65 is adapted to open and close the port 40 above referred to as admitting vacuum to the common chamber 37. The port 40 leads into the 10 vacuum chamber 63 and naturally the raising of the disk 65 admits the vacuum to the chamber.

Applicant has now described his device with running comment as to method of operation. Details of passageways, tubes, pneumatics and valves are necessarily incident to such a description, and applicant of course does not wish to limit himself to any specific form or shape of pouches, valves, 20 passageways and the like.

Applicant does not desire by his description of details, without calling attention to the possibility of the use of other details of like function, to limit himself to any more 25 detailed construction than that set out in his claims.

Having thus described my invention, what I claim as new and desire to secure by Letters Patent, is:—

30 1. In a player piano, a power pneumatic having a movable member, an air cushion stop for said movable member, means for varying the pressure of air in the said air cushion, and means independent from said 35 varying means for deflating said air cushion whereby said cushion is withdrawn as a stop.

2. In a player piano, the combination with a series of power pneumatics and air cushion stops therefor, of means of exhausting the 40 air in the air cushion stops in selected pneumatics of the series, and means of varying the pressure of the air in the remainder of the air cushion stops of said series without affecting said selected pneumatics and stops.

45 3. In a player piano, a power pneumatic having a movable member, an air cushion stop for said movable member, and means for varying the pressure of air in the said air cushion above or below atmosphere.

50 4. In a player piano, a power pneumatic having a movable member, an air cushion stop for said movable member, means for varying the pressure of air in the said air cushion above or below atmosphere, and 55 means independent from the said varying means for deflating said air cushion whereby said cushion is withdrawn as a stop.

5. In a player piano, a power pneumatic having a movable member, an air cushion 60 stop for said movable member, means for varying the pressure of air in the said air cushion above or below atmosphere, and means for deflating said air cushion comprising a vacuum chamber, a pouch therein, 65 connection from the chamber to said cushion,

ion, and a valve on the pouch, said valve positioned to cut off the means of varying pressure and to open the connection between the vacuum chamber and said cushion.

6. A means of controlling a primary and auxiliary pneumatic, comprising a tracker board having a slot therein, a primary and an auxiliary pneumatic, connection from each to the slot, means in connection with the primary pneumatic for operating a desired device, said primary pneumatic being adapted to respond to all exposures of the tracker slot, said auxiliary pneumatic being adapted to respond only to full exposures of the slot, and a roll adapted to pass 80 over the tracker slot, and having slots of partial and full width for partial and full exposures of the slot.

7. A means of controlling a primary and auxiliary pneumatic, comprising a tracker 85 board having a slot therein, a primary and an auxiliary pneumatic, connection from each to the slot, means in connection with the primary pneumatic for operating a desired device, said primary pneumatic having 90 a sensitive pouch adapted to respond to all exposures of the tracker slot, said auxiliary pneumatic having a less sensitive pouch adapted to respond only to full exposures of the slot, and a roll adapted to pass over 95 the tracker slot, and having slots of partial and full width for partial and full exposures of the slot.

8. In a player piano, a tracker having a slot therein, a power pneumatic having a 100 movable member, an air cushion stop for said member, a pneumatic for controlling the power pneumatic, a pneumatic for controlling the air cushion stop, connection for both pneumatics with the said tracker bar 105 slot, with the pouches of said pneumatics of varying sensitiveness for the purpose described.

9. In a player piano, a power pneumatic having a movable member, an air cushion 110 stop for said movable member, a pneumatic adapted to control the power pneumatic, a pneumatic adapted to control the air cushion stop, a tracker having a slot therein, a roll having perforations of different width to 115 partially and wholly expose said slot, connection for both controlling pneumatics with the said tracker bar slot, with the pouches of said pneumatics of varying sensitiveness for the purpose described. 120

10. A player piano, a series of power pneumatics having movable members with air cushion stops for said members, means for varying the pressure of air in the said air cushions above or below atmosphere, and 125 means for deflating selected air cushions of the series comprising a series of vacuum chambers, pouches therein, connections therefrom to said air cushions, and valves on the pouches, said valves positioned to cut 130

off the means of varying pressure and to open the connection between the vacuum chambers and the said air cushions.

11. In a player piano, a series of power pneumatics having movable members, with air cushion stops for said members, means for varying the pressure of air in the said air cushions above or below atmosphere, a series of pneumatics adapted to control the power pneumatics, a series of pneumatics adapted to control the air cushion stops, a tracker having slots therein, a roll having

perforations of different width adapted to partially expose said slots and to wholly expose selected slots, connections for each of the controlling pneumatics of the series, with a tracker bar slot, with the pouches of the air cushion pneumatics so tough as to require full exposure of the slots for the purpose described. 35
